[57] ABSTRACT

A control for operating a fluid actuated device includes an electrically actuated pilot valve for controlling flow of pressurized fluid to the device. The pilot valve has an electromagnet for actuating the valve against a high resistance to being initially opened and a much lower resistance to being maintained in the open state. An electrical control circuit initially introduces a high potential to the electromagnet to open the valve and subsequently introduces a low potential to the electromagnet to maintain the valve in the open state, whereby the fluid activated device is maintained in the actuated state with significantly less power than that used to initially actuate the device.

ELECTROMAGNET CONTROL APPARATUS

The present invention relates generally to controls for reducing the power consumption of an electromagnet and more specifically to electrically operated devices for determining the flow of fluid to a fluid actuated device.

When a well is drilled in relatively deep water, as from an ocean floor, it is often desirable to drill and complete the well at the ocean floor with devices which can be remotely controlled from a location above the surface of the water. A plurality of these devices, which may include blowout preventers, hydraulic connectors, and valves, may be employed in controlling different functions on a single well. Usually these devices are remotely operated by a pressurized fluid which is controlled by appropriate actuation of solenoid actuated pilot valves. When a solenoid is energized, the pilot valve is opened and the pressurized fluid is directed to the device.

In the past, apparatus for controlling the energizing of the solenoid or electromagnet in each of the pilot valves has included a source of relatively high operating potential and a switch for selectively introducing the high potential to the electromagnet. Thus, by operation of the switch, the electromagnet has been energized to open or otherwise activate the valve and activate the device.

It is often necessary to activate the devices for an extended period of time. Under such circumstances, the high potential introduced to each solenoid is continued in maintaining the pilot valve in its actuated or open state. However, at the relatively high energizing potential, each pilot valve previously used has consumed as much as 360 watts of power. The generation of electric power at the offshore location of a subsea well is expensive, the high power consumption of each valve being correspondingly costly. This problem has been compounded by the multiplicity of pilot valves which may be provided at each well. For example, a typical installation including seven pilot valves has previously consumed about 2,500 watts of power. In order to carry this amount of electricity to the remote locations, such as the ocean floor, large expensive transmission lines are required.

The high power consumption has also been critical with respect to the reliability of the pilot valves. When energized over an extended period of time, the solenoids or electromagnets have overheated, resulting in their unreliability and failure. Failure of a pilot valve obviously requires its replacement at great cost.

In the present invention, a pilot valve includes an electromagnet having a coil and a plunger or armature initially biased to an extended or one position when the coil is deenergized, and drawn to another or proximate position when the coil is energized. This movement of the plunger opens or otherwise operates a valve connected to the plunger, controlling the flow of a pressurized fluid that actuates a device.

A relatively large force must be used to initially overcome the bias on the plunger. However, once the plunger is in its proximate position, a force of significantly less magnitude can be relied upon to maintain this disposition. For example, when the plunger is in the extended position, about 360 watts may be required to move the plunger to the proximate position; however,

the plunger can be maintained in the proximate position with only about two watts of power.

In one example of the invention, a control apparatus is provided with a first source of relatively low operating potential and a second source of relatively high operating potential. A first relay, having first and second sets of contacts, and a second relay, having third and fourth sets of contacts, are also provided. The second source of operating potential is introduced through the fourth set of contacts to the coil of the electromagnet. The first potential is introduced through the second and third sets of contacts to the coil in the electromagnet. A coil in each of the first and second relays is connected through a first switch to the first source of operating potential. Additionally, the coil in the first relay is connected through the first contacts and a second switch to the first source of operating potential. Except for the second switch and the third contacts, each of the contacts and switches is normally open.

When the first switch is closed, the first and second relays are activated so that the high potential is switched to the electromagnet and the plunger is drawn from the extended to the proximate position. If the first switch is then opened, the second switch, which is normally closed, will continue to energize the first relay through the first contacts. The second relay, however, will be deactivated so that the low potential is introduced to the electromagnet. This low potential can maintain the pilot valve in the state to which it has been shifted by the plunger in moving to its proximate position, until the second switch is opened and the plunger is returned or biased to its extended position.

These features of the control apparatus are of significant advantage, especially where electromagnets and solenoids must be actuated at remote locations from the control apparatus. Whereas seven of the devices of the prior art, for example, might consume as much as about 2,500 watts, the device of the present invention would consume only about as much power as a 15 watt light bulb. Not only is the cost of the electricity consumed lower, but the size of the transmission lines can be substantially decreased. Furthermore, the pilot valves will not overheat making them considerably more reliable over extended periods than the devices of the prior art.

This invention possesses many other advantages, and has other purposes which may be made more clearly apparent from a consideration of a form in which it may be embodied. This form is shown in the drawings accompanying and forming part of the present specification. It will now be described in detail, for the purpose of illustrating the general principles of the invention; but it is to be understood that such detailed description is not to be taken in a limited sense.

To satisfactorily complete a well on the floor of the ocean, numerous fluid actuated devices, such as flow-out preventers, hydraulic connectors, and valves are employed. One such fluid actuated device 11 is illustrated schematically in FIG. 1. A completion control pod 13 is adapted to have a high pressure fluid line assembly 15 connected thereto extending from a suitable source, such as a drilling vessel floating in the water, this assembly including a flexible hose 19 and electrically conductive wires 17 to control the operation of the fluid actuated device 11. The supply hose 19 is adapted to conduct fluid at a desired pressure to the devices 21, 31 in the pod 13 and to the fluid actuated device 11 itself.

A pilot valve 21 is connected to the signal wires 17 and communicates with the supply hose 19, providing a means for controlling fluid flow to the fluid actuated device 11. This pilot valve controls the flow of fluid to a control valve 31, that, in turn, controls the flow of the fluid passing through the lines 15, 19 to the device 11.

Actually, a plurality of sets of a pilot valve 21, control valve 31 and fluid actuated device 11 are disposed at the ocean floor to control different functions relating to the well extending downwardly from the ocean floor. However, for simplicity of illustration, only a single set of pilot valve, control valve and fluid actuated device is illustrated in the drawings.

The control pod 13 includes a main body 12 having a passage 14 therethrough connected to the supply hose 19 for conducting fluid under pressure to an inlet or supply 25 of the pilot valve 21. This port communicates with an inlet passage 25a in an outer body 25b that communicates with a passage 67 in a pusher 67a disposed within a radial opening 67b in an inner valve body 25c, this pusher member bearing against a radial shear seal 25d extending inwardly of the body 25c and adapted to bear against the upstream side of 59a of a gate valve 59 movable longitudinally in the inner body. The pusher member is adapted to be acted upon by the fluid pressure in the inlet passage 25a to be urged inwardly and to be retained in sealed relation against the seal element 25d, in turn holding such seal element bearing against the upstream face 59a of the gate valve member.

As disclosed in FIG. 2, the pilot valve 21 is in a closed position, in that a lateral passage 61 extending through the gate 59 is out of alignment with the shear seal 25d. The gate valve is located in the closed upper position, illustrated in FIG. 2, by engagement of an upwardly extending shoulder 59b thereon against a companion shoulder 59c on an adapter plate 200 suitably secured to the outer body member 25b, as by means of screws 201. The gate valve member 59 is shiftable to an open condition, as described hereinbelow, to bring a lower stop shoulder 202 thereon against a companion lower shoulder 203 on the inner valve body 25c, which effects alignment of the transverse passage 61 through the gate

valve member with the inlet shear seal 25d and also with an outlet shear seal element 204 bearing against the downstream side 205 of the gate valve member, the element 204 engaging a radially disposed pusher member 206 mounted within the valve body 25c, the fluid flowing through the shear seal 204 and the pusher member 206 into an outlet passage 29a communicating with an outlet port 29 that, in turn, communicates with an outlet passage 29b extending to an inlet port 39 of the control valve 31.

When the gate valve member 59 is in its upper or closed position (FIG. 2), the fluid in the outlet passage 29a can exhaust through the downstream pusher member 206 and shear seal 204 into an exhaust passage 63 provided in the gate valve member, this exhaust passage opening into an outlet passage 27a in the valve body 25c extending to an exhaust port member 27 that communicates with a suitable exhaust line (not shown) that may extend to any suitable location, as to the vessel or drilling platform at the surface of the water.

To facilitate shifting of the gate valve member 59, which is a flat, plate-like member, between its closed and opened positions, its downstream face 205 bears against spaced rollers 65 suitably rotatably mounted in the valve body 25c, as through the aid of needle bearings (not shown). Thus, the pressure of the fluid in the inlet passage 25a and bearing against the upstream face 59a of the gate valve member forces the latter against the rollers 65, but the rolling engagement between the downstream face 205 of the gate valve member and the rollers facilitates shifting of the gate valve member between its closed and opened positions.

The lower portion 220 of the gate valve is cylindrical, being slidable within a companion bore 221 in the inner valve body 25c. Similarly, the upper portion 222 of the valve member is cylindrical, being slidable through a companion axial bore 223 in the adapter 200, this upper cylindrical portion being suitably secured to a valve operating stem 69, as by means of transverse pins 229. The outer stem is disposed within an electromagnetic or solenoid assembly 41 suitably secured to the adapter 200.

The solenoid assembly includes an outer magnetic core 51 secured to an inner magnetic core 52 by radial screws 53 bearing against a tapered face 54 on the lower flange 55 of the inner core, which bears against a downwardly facing shoulder 55a in the outer core 51. Between the inner and outer cores is disposed the coil 47 of the electromagnetic or solenoid, the windings of which are connected to the signal wires 17, that may extend through the hose assembly 15 to the operating location on the drilling vessel or platform at the top of the water. The pilot valve 21 is initially urged to the closed position, illustrated in FIG. 2, by a helical compression spring 57, the lower end of which bears against a shoulder 56 on the inner core 52 and the upper end of which bears against a magnetic plunger 53a threadedly or otherwise suitably attached to the upper end of the stem 69 and locked thereto by a suitable lock nut 240 threaded on the stem. When the circuit to the solenoid 41 is open, the spring 57 pushes the valve stem 69 and the plunger 53a to an extended position, the inner tapered end 241 of the plunger being spaced from the companion tapered end 242 of the inner core 52 by a predetermined distance, providing a gap 55a therebetween. A sleeve 243 is clamped between the upper end of the outer core 51 and an upwardly facing shoulder

244 on the inner core 52, the periphery 245 of the plunger or armature 53a having a suitable clearance with respect to such sleeve.

When the circuit to the solenoid coil 47 is completed, the plunger 53a is attracted inwardly to shift the gate valve member 59 to the open position in which its lateral passage 61 is in alignment with the shear plugs 25d, 204. This position is determined by the engagement of the lower stop shoulder 202 with the companion shoulder 203 in the inner valve body 25c. At this time, the gap 55a between the plunger 53a and the inner core 52 has been reduced considerably. By way of example, the gap 55a, prior to the energizing of the electromagnet, may be about 0.200 inches; whereas, the gap 55a, with the electromagnet energized, may be about 0.030 inches. Thus, in the specific pilot valve 21 disclosed, it is initially disposed in a closed position when the electromagnet is deenergized, and is shifted to the open position and retained in such open position when the electromagnet is energized.

The control valve 31 includes a valve body 300 having an actuating port member 301 communicating with the outlet or discharge passage 29a, 29b of the pilot valve, an outlet port member 302 communicating with the passage 37a in the pod body 12 that leads to the fluid activated device 11, a supply port member 303 communicating with the source of fluid pressure flowing through the passage 14 in the body from the high pressure hose 19, and an exhaust port member 304 communicating with an exhaust passage (not shown) that may extend to a suitable exhaust line (not shown).

A shiftable valve member 305 is movable within the valve body 300, this valve member extending across the exhaust, outlet and inlet port members 304, 302, 303. As disclosed, the inlet 303 is closed, but the passage 37a leading to the fluid activated device 11 communicates through a passage 310, 310a, 310b in the shiftable valve member with the exhaust port member 304, as illustrated in FIG. 3. The valve member 305 is shifted and retained in this position by a helical compression spring 311 disposed within the valve body housing extension 300a, the outer portion of the spring bearing against an end wall 312 of the housing, and the inner portion of the spring bearing against a head 313 threadedly or otherwise suitably secured to the movable valve member 305, shifting a shoulder 314 on this valve member into engagement with a companion stop shoulder 315 in the valve body 300. At this time, the passage 37a leading to and from the fluid activated device 11 is in an exhaust condition, in which no fluid pressure is supplied to the device 11.

When the electromagnet coil 47 is energized to pull the plunger 53a inwardly, which acts through the valve stem 69 to shift the gage member 59 to the valve opening position, at which its transverse passage 61 is aligned with the shear seals 25d, 204, fluid under pressure flows through the line 29a, 29b and through the seal sub 301 that communicates with the head end 320 of a cylinder 321 containing the piston portion 322 of the shiftable valve member 305. The fluid under pressure shifts the valve member 305, as to the right illustrated in FIG. 3, to place the port 310a in communication with the inlet port 303 and the other port 310b in communication with the outlet port 302 of the control valve 31. This position is determined by engagement of a shoulder 325 on the valve member 305 with a com-

panion shoulder 326 on the closure portion 327 of the control valve body. Fluid under pressure can then flow from the supply hose 19 to the inlet port 303, and then through the valve member passages 310a, 310, 310b, to the outlet port 302, and then through the body passage 37a to the fluid activated device 11. The deenergizing of the solenoid or electromagnet 41 will cause the spring 57 to shift the pilot valve to its initial position in which the fluid passage 29b, 29a communicates through the exhaust path 63 in the gate valve 59 to the exhaust line 27a, thereby relieving the fluid pressure in the cylinder 321, which will then permit the control valve spring 311 to shift the valve member 305 back to its initial position, in which the fluid line 37a leading to the fluid activated device 11 communicates through the path 302, 310a, 310, 310b to the exhaust port member 304 and the exhaust line.

In both the pilot valve and the control valve, suitable seal rings are provided to prevent fluid leakage between the several parts, as shown.

The present invention involves the fact that the plunger 53a can be maintained in its proximate position with less power than that used to draw the plunger 53a from its extended position to its proximate position. This can be generally explained with reference to the dimensions of the gap 55a. When the gap 55a is relatively large, a larger force is needed to overcome the bias of the spring 57 than when the gap 55a is relatively small. By way of example, it has been found that the plunger 53a can be moved to its proximate position with about 300 watts of power and maintained in its proximate position with less than about 2 watts of power. It can be appreciated that in the interest of conserving electricity, it is particularly advantageous to reduce the power to the coil 47 after the device 11 has been initially activated, especially if the device 11 is to remain activated for an extended period of time. This not only will reduce the consumption of power, but also 40 the heat buildup within the pilot valve 21.

An electrical circuit 71 providing these advantages is illustrated schematically in FIGS. 4 through 7. Generally, the electrical circuit 71 includes first and second sources of operating potential 73 and 75, respectively. The first source 73 provides a relatively low potential, such as 24 volts, while the second source 75 preferably provides a relatively high potential, such as 90 volts. Switching means, shown generally at 77, is connected to the sources of potential 73 and 75 to selectively energize the pilot valve 21 with one of the higher and lower operating potentials.

The switching means 77 can include a first relay 79 having a coil 81 and first and second sets of contacts 83 and 85, respectively. A second relay 87 can be similarly provided with a coil 89 and third and fourth sets of contacts 91 and 93, respectively. The first, second and fourth contacts, 83, 85 and 93, respectively, normally provide an open circuit while the third set of contacts 91 normally provides a closed circuit.

A normally open switch 95 is connected between the first source 73 and the coils 81 and 89 to selectively energize the first and second relays 79 and 87, respectively, with the lower potential. The coil 81 is also connected to one of the first contacts 83. The other of the first contacts 83 is connected through a normally closed switch 97 to the first source of operating potential 73.

A conductor 99 provides continuity between the first source 73 and one of the second contacts 85. Similarly, a conductor 101 provides continuity between the other of the second contacts 85 and one of the third contacts 91. The other of the third contacts 91 is connected through the signal wire 17 to the connector 45. A third conductor 103 is connected between the source of operating potential 75 and one of the fourth contacts while the other of the fourth contacts 93 is connected through the signal wire 17 to the connector 45. The normally open switch 95 and the normally closed switch 97 are preferably push button switches which are biased to provide their normal characteristics.

The structural features set forth above provide the switching means 77 with at least four modes of operation. A first mode of operation, wherein the coil 47 of the pilot valve 21 is deenergized, is illustrated in FIG. 4. With each of the contacts 83, 85, 91 and 93, and each of the switches 95 and 97 disposed in their normal states, as previously described and illustrated in FIG. 4, the coil 47 is deenergized so that the pilot valve 21 and control valve 31 are in their exhaust conditions, the device 11 being deactivated.

When the push-button switch 95 is closed, the first and second relays, 79 and 87 are energized. In this second mode of operation, illustrated in FIG. 5, the first, second and fourth contacts 83, 85, 93 provide closed circuits, while the third contacts 91 provide an open circuit. This enables the source of higher operating potential 75 to be connected through the conductor 103, the fourth contacts 93 and the conductors 17 to the coil 47. In response to the energizing of the coil 47, the plunger 53a is drawn into its proximate position to shift the valve 21 to its open condition, causing fluid under pressure to flow into the control valve member 305 to its open condition in which fluid under pressure can flow from the pressure line 19 through the inlet and outlet passages 14, 37a to the device 11, to actuate the latter.

It will also be noted that the energizing of the relay 79 completes a circuit through the first contact 83 so that the coil 81 is also energized by the lower operating potential 73 through the second switch 97. This alternate path for energizing the coil 81 gives rise to the third mode of operation illustrated in FIG. 6. As soon as pressure is relieved from the push button switch 95 and it returns to its normally open position, the second relay 87 is deenergized and the third and fourth contacts 91 and 93 return to their normally closed and normally open states, respectively. However, the first relay 79 remains energized through the switch 97 and the first contacts 83 so that the second contacts 85 continue to provide a closed circuit. The lower potential from the source 73 is then introduced through the conductor 99, the second contact 85, the conductor 101, the third contact 91 and the signal wires 17 to the coil 47. This lower potential is sufficient to maintain the plunger 53a in its proximate position so that the device 11 can remain activated for an extended period without overheating the pilot valve 21.

To deactivate the device 11, the normally closed switch 97 can be pressed and opened to deenergize the coil 81, as illustrated in FIG. 7, providing the fourth mode of operation in which the first and second contacts 83, 85 return to their initial open state, the third and fourth contacts 91, 93 remaining in their closed and open states, respectively. When the push

button switch 97 is released, it returns to its normally closed state, and the circuit 71 returns to its first mode of operation (FIG. 4).

The switches 95 and 97 can be disposed on an operating panel (not shown) to provide the simplest of operating procedures wherein the push button switch 95 is pressed to effect activation of the device 11, the push button switch 97 being pressed to effect deactivation of the device 11.

Though the operating procedure is simple, the electrical circuit 71 provides significant advantages in the operation of the electromagnet assembly 41. In order to initially draw the plunger 53a into its proximate position and thereby cause the device 11 to be actuated, the higher operating potential 75 is introduced to the coil 47. Continued energizing of the coil 47 with the high operating potential 75 would retain the plunger 53a in the proximate position, but it might also result in overheating of the pilot valve 21. However, as soon as the plunger 53 moves to the proximate position and the push button switch 95 is released, the electrical circuit 71 automatically switches the lower potential 73 to the coil 47 to maintain the plunger 53a in its proximate position. The lower potential decreases the amount of current drawn by the electromagnet assembly 41 and significantly reduces the power consumption of the pilot valve 21. In the example given above, the power consumption is reduced several times, as from 320 watts in a single pilot valve to about 2 watts. With a reduced current in the coil 47, there is no danger of failure due to overheating. The effective life of the pilot valve 21 is substantially increased along with its reliability.

The reduced current is especially appreciated when it is realized that the signal wires 17 which carry the current can be reduced in size. This is of paramount significance when the electricity is transmitted to a remote location such as the floor of the ocean.

I claim:

1. In apparatus for effecting operation of a fluid actuated device: valve means operatively connectable to a source of fluid pressure and to the device, said valve means including a valve member shiftable between a first position preventing flow of fluid from the source to the device and a second position permitting flow of fluid from the source to the device; an electrically actuated means operatively connected to said valve member for shifting said valve member from one of said positions to the other of said positions; means for supplying electric power of a first particular value to said electrically actuated means to effect shifting of said valve member from said one position to said other position; and means for supplying electric power to said electrically actuated means of a second particular value substantially less than said first value to retain said valve means in said other position; said electric power of a first value comprising a first source providing a relatively high potential; said electric power of a second value comprising a second source providing a relatively lower potential than said high potential; switching means for selectively connecting said first source of high potential to said electrically actuated means to shift said valve member to said other position or for connecting said second source of lower potential to said electrically actuated means to retain said valve member in said other position; wherein said switching means comprises a first relay selectively energizable by

the lower potential to introduce the higher potential to the electrically actuated means, a second relay connected to the first relay and energizable to introduce the lower potential to the electrically actuated means, a first normally open switch connected to the source of lower potential and operable to simultaneously energize the first and second relays so that the lower potential is introduced to the second relay and the high potential is introduced to the electrically actuated means, and means for continuing current flow from the lower potential through the second and first relays to the electrically actuated means after the first switch is opened to reduce the power consumed and maintain the valve member in said other position.

2. In apparatus for effecting operation of a fluid actuated device: valve means operatively connectable to a source of fluid pressure and to the device said valve means including a valve member shiftable between a first position preventing flow of fluid from the source to the device and a second position permitting flow of fluid from the source to the device; an electrically actuated means operatively connected to said valve member for shifting said valve member from one of said positions to the other of said positions; means for supplying electric power of a first particular value to said electrically actuated means to effect shifting of said valve member from said one position to said other position; and means for supplying electric power to said electrically actuated means of a second particular value substantially less than said first value to retain said valve means in said other position; wherein said one of said positions is said first position and said other of said positions is said second position; said electric power of a first value comprising a first source providing a relatively high potential; said electric power of a second value comprising a second source providing a relatively lower potential than said high potential; switching means for selectively connecting said first source of higher potential to said electrically actuated means to shift said valve member to said second position or for connecting said second source of lower potential to said electrically actuated means to retain said valve member in said second position; wherein said switching means comprises a first relay selectively energizable by the lower potential to introduce the higher potential to the electrically actuated means, a second relay connected to the first relay and energizable to introduce the lower potential to the electrically actuated means, a first normally open switch connected to the source of lower potential and operable to simultaneously energize the first and second relays so that the lower potential is introduced to the second relay and the high potential is introduced to the electrically actuated means, and means for continuing current flow from the lower potential through the second and first relays to the electrically actuated means after the first switch is opened to reduce the power consumed and maintaining the valve member in said second position.

3. In apparatus for effecting operation of a fluid actuated device: valve means operatively connected to a source of fluid pressure and to the device, said valve means including a valve member shiftable between a first position preventing flow of fluid from the source to the device and a second position permitting flow of fluid from the source to the device; an electromagnet having a coil; a plunger connected to said valve member for shifting said valve member from one of said po-

sitions to the other of said positions, said plunger being shiftable from an extended position spaced from said electromagnet to a proximate position substantially closer to said electromagnet; means for supplying electric power of a first particular value to said coil to effect shifting of said plunger from extended position to proximate position; and means for supplying electric power to said coil of a second particular value substantially less than said first value to retain said plunger in said proximate position; said electric power of a first value comprising a first source providing a relatively high potential; said electric power of a second value comprising a second source providing a relatively lower potential than said high potential; switching means for selectively connecting said first source of high potential to said coil to shift said plunger from said extended position to said proximate position or for connecting said second source of lower potential to said coil to retain said plunger in said proximate position; wherein said switching means comprises a first relay selectively energizable by the lower potential to introduce the higher potential to the coil, a second relay connected to the first relay and energizable to introduce the lower potential to the coil, a first normally open switch connected to the source of lower potential and operable to simultaneously energize the first and second relays so that the lower potential is introduced to the second relay and the high potential is introduced to the coil, and means for continuing current flow from the lower potential through the second and first relays to the coil after the first switch is opened to reduce the power consumed and maintaining the plunger in said proximate position.

4. In apparatus for effecting operation of a fluid actuated device: valve means operatively connected to a source of fluid pressure and to the device, said valve means including a valve member shiftable between a first position preventing flow of fluid from the source to the device and a second position permitting flow of fluid from the source to the device; an electromagnet having a coil; a plunger connected to said valve member for shifting said valve member from one of said positions to the other of said positions, said plunger being shiftable from an extended position spaced from said electromagnet to a proximate position substantially closer to said electromagnet; means for supplying electric power of a first particular value to said coil to effect shifting of said plunger from extended position to proximate position; and means for supplying electric power to said coil of a second particular value substantially less than said first value to retain said plunger in said proximate position; wherein said one of said positions is said first position and said other of said positions is said second position; said electric power of a first value comprising a first source providing a relatively high potential; said electric power of a second value comprising a second source providing a relatively lower potential than said high potential; switching means for selectively connecting said first source of high potential to said coil to shift said plunger to said proximate position or for connecting said second source of low potential to said coil to retain said plunger in said proximate position; said switching means comprising a first relay selectively energizable by the lower potential to introduce the higher potential to the coil, a second relay connected to said first relay and energizable to introduce the lower potential to the coil, a first normally

open switch connected to the source of lower potential and operable to simultaneously energize the first and second relays so that the lower potential is introduced to the second relay and the higher potential is introduced to the coil, and means for continuing current flow from the lower potential through the second and first relays to the coil after the first switch is opened to reduce the power consumed and maintaining the plunger in said proximate position.

5. In an apparatus for controlling operation of a fluid actuated device: Valve means operable connectable to a source of fluid pressure and to the device, said valve means including a valve member shiftable between a first position preventing flow of fluid from the source to the device and a second position permitting flow of fluid from the source to the device; an electrically actuated means operatively connected to said valve member for shifting said valve member from one of said positions to the other of said positions;

a first source providing a relatively high electric potential; a second source providing a relatively low electric potential;

a first relay selectively energizable by the lower potential to introduce the higher potential to the electrically actuated means, a second relay connected to the first relay and energizable to introduce the lower potential to the electrically actuated means, a first normally open switch connected to the source of lower potential and operable to simultaneously energize the first and second relays so that the lower potential is introduced to the second relay and the high potential is introduced to the electrically actuated means, and means for continuing current flow from the lower potential through the second and first relays to the electric-

cally actuated means after the first switch is opened to reduce the power consumed and maintain the valve member in said other position.

6. In apparatus as defined in claim 5; wherein said one of said positions is said first position and said other of said positions is said second position.

7. In apparatus for effecting operation of a fluid actuated device: valve means operatively connected to a source of fluid pressure and to the device, said valve means including a valve member shiftable between a first position preventing flow of fluid from the source to the device and a second position permitting flow of fluid from the source to the device; an electromagnet having a coil; a plunger connected to said valve member for shifting said valve member from one of said positions to the other of said positions, said plunger being shiftable from and extended position spaced from said electromagnet to a proximate position substantially closer to said electromagnet; a first source providing a relatively high electric potential; a second source providing a relatively low electric potential; a first relay selectively energizable by the low potential to introduce the higher potential to the coil, a second relay connected to the first relay and energizable to introduce the lower potential to the coil, a first normally open switch connected to the source of lower potential and operable to simultaneously energize the first and second relays so that the lower potential is introduced to the second relay and the high potential is introduced to the coil, and means for continuing current flow from the lower potential through the second and first relays to the coil after the first switch is opened to reduce the power consumed and maintaining the plunger in said proximate position.
